UNITED STATES PATENT OFFICE.

ESTON RICKETSON AND ROBERT V. DAY, OF DOUGLAS, GEORGIA.

STUMP PULLER.

Application filed June 2, 1924. Serial No. 717,400.

To all whom it may concern:

Be it known that we, ESTON RICKETSON and ROBERT V. DAY, citizens of the United States, residing at Douglas, in the county 5 of Coffee and State of Georgia, have invented new and useful Improvements in Stump Pullers, of which the following is a specification.

This invention relates to stump pullers 10 and has for its object the provision of a novel device so constructed and arranged as to utilize a tractor as the means for applying power to a winding mechanism for applying a pull to a flexible member engaged 15 about the stump to be pulled.

An important object is the provision of a device of this character including a skid onto which the tractor may be driven and provided with means for supporting the 20 tractor in such manner that the rear axle thereof will be in operative engagement with the transmission mechanism for the winding drum.

Another object is the provision of a skid 25 device so constructed and arranged that it may freely slide over the ground so as to accommodate itself automatically to the line of pull between the anchor and the stump to be extracted, and to move easily from one 30 anchor to another.

A further object is the provision of a device of this character in which means is provided for guiding the flexible member, cable or the like, during the skidding or 35 shifting movement so as to prevent any strain upon or binding of the winding mechanism.

Another important feature is the provision 40 of a clutch means associated with and forming a part of the winding mechanism whereby the transmission may be thrown into inactive position to permit unreeling of the flexible member without there being any movement imparted to the various gears 45 of the transmission.

Still another object is the provision of a novel brake mechanism associated with the winding drum for the purpose of checking the rotation thereof and preventing back 50 lash when unreeling the cable.

An additional object is the provision of an apparatus of this type which will be comparatively simple and inexpensive to manufacture, which, with minor alterations or 55 modifications, may be capable of having any ordinary type or make of tractor mounted

thereon and which will, moreover, embody various structural features of advantage which will insure positiveness in operation, efficiency in action, durability in service, and 60 which will constitute a general improvement in the art.

With the above and other objects and advantages in view, the invention consists in the details of construction to be herein-after more fully described and claimed, and illustrated in the accompanying drawings, in which:

Figure 1 is a side elevation of the complete device showing a tractor mounted 70 thereon in operative position.

Figure 2 is a side elevation showing the tractor dismounted from the skid and showing the skid arranged for transportation from place to place. 75

Figure 3 is a top plan view.

Figure 4 is a cross section on the line 4—4 of Figure 1.

Figure 5 is a section on the line 5—5 of Figure 4. 80

Figure 6 is a detail section showing an elevation of the brake mechanism.

Figure 7 is a detail cross section on the line 7—7 of Figure 6. 85

Figures 8 and 9 are detail views of the coating clutch element.

Figure 10 is a fragmentary detail section showing the interengagement of the clutch element, and the ratcheting effect.

Figures 11 and 12 are detail views illustrating a modified form of clutch. 90

Figure 13 is a detail sectional view through the cable guide located at the front of the device.

Figure 14 is a section on the line 14—14 95 of Figure 13.

Figure 15 is a detail sectional view through one of the gears attached to the rear spindles of the tractor.

Figure 16 is an end view thereof. 100

Figure 17 is a plan view of the supporting skid, the frame members being in section and certain other parts being broken away.

Figure 18 is a section on the line 18—18 105 of Figure 17.

Figure 19 is a cross section on the line 19—19 of Figure 18, and

Figures 20, 21 and 22 are fragmentary detail views. 110

Referring more particularly to the drawing, the letter A designates the support-

ing base or skid as a whole, which is here shown as including longitudinal bars or sills 1 connected at intervals by cross bars 2 and having secured thereto a bottom 3 with upwardly inclined sides and ends. A platform 4 is preferably secured upon the longitudinal and cross bars and secured to the underneath side of the bottom 3, is a pan-like skid member 5 which has its intermediate portion flat to bear upon the ground and which has its edges and ends inclined as shown at 6. The purpose of having this pan-shaped sheathing on the underside will be hereinafter explained. The intermediate portion of the platform or base A has secured thereon longitudinally extending bars 7 held as for instance by the bolts 8 which pass through the cross bars 2, and projecting beyond the forward end as shown at 9. While certain details of this base have been described it should be distinctly understood at this point that there is no restriction whatsoever as to the specific arrangement of bars and other elements inasmuch as they may be varied within wide limits, the essential feature being merely that there is the pan-shaped lower or skid surface whereby the device may slide on the ground to accommodate itself to the line of draft between the anchor and the stump to be extracted as will be described.

Secured upon and rising from the rear portion of the base and spaced inwardly from the sides thereof are frames designated broadly by the letter B. Each of these frames might conveniently be constructed as a single casting, though if preferred they might be constructed of any suitable number of parts secured together in any preferred manner and firmly secured to the platform or base A by any preferred means such as that disclosed. For bracing purposes we provide stay rods 10 which extend through the frames B at various points and which insure a strong and rigid structure. The upper edges of these frames are formed with saddle portions 11 designed to support the rear axle housing C of an ordinary tractor indicated at D. Secured upon the upper edges of these frames are caps 12 which embracingly engage the axle housing C and which operate to prevent the tractor from any displacement.

At the rear portions of the frames B are bearings 13 for a horizontal shaft 14 upon the ends of which are keyed or otherwise secured large gears 15 which mesh with idler gears 16 carried by a transverse shaft 17 journaled through suitable bearings 18 on the frame members B.

In order to mount the tractor in position, it is necessary to back it up onto the base A, the rear wheels E being of course in place on the rear spindles F and traveling along the platform at the side edges thereof. The

tractor is moved to a position adjacent the forward ends of the frame members B, and a billet of wood or the like is then laid upon the base in such position that when the tractor is additionally driven the cleat 70 commonly provided on the rear wheels will engage the billet and ride up thereon. In this way the rear part of the tractor is elevated to such an extent that the rear axle housing will be located above and will drop into the saddles 11, after which the caps 12 are placed in position and bolted down to hold the tractor in position. Subsequently to this, the tractor wheels E are removed, and secured then upon the spindles F, and held by the usual nuts G, are sleeves 19 having their inner ends formed as gears 20 which mesh with the idler gears 16. When these various things have been done, it is quite apparent that when the tractor is operated the shaft 14 will be rotated through the medium of the gears.

Rotatably mounted upon the shaft 14 between the frames B is a drum or windlass 21 having side flanges 22 and 23 and having secured thereto and wrapped thereabout a cable 24 which has its free end extending along the base and passing through a guide device mounted on the extension 9. The extremity of this cable is intended to be connected with the stump to be pulled.

The guide device referred to is designated broadly by the letter H and includes a frame 25 formed or mounted upon the extension 9 and having journaled therein pairs of vertical rollers 26 and horizontal rollers 27 between which the cable 24 passes. The purpose of this guide device is to keep the cable always in a position along the longitudinal axis of the complete device. It should also be mentioned in passing that the forward extremity of the extension 9 is provided with a hole 28 for engagement therein or connection therewith of any suitable draft device such as the coupling pin 110 for the draw-bar of the tractor so that the device may be transported.

Within one end of the drum 21 is a clutch face 29 either formed upon or secured to the drum and cooperating with a clutch face 30 on a sleeve 31 or collar which is splined upon the shaft 14 and which is grooved for engagement by the pins 31^a projecting inwardly from the opposite sides 32 of a shifting lever 33 pivotally mounted as shown at 34. It will of course be seen that by shifting this lever in one direction or the other the clutch members may be engaged or disengaged at will whereby to control the rotation of the drum. The advantage in providing this clutch device is that the drum may be permitted to run absolutely freely when unreeling the cable 24 for the purpose of carrying it to and engaging it upon the stump to be extracted. This clutch device 130

makes it unnecessary for all the gearing in the transmission to be rotated when the cable is unreeled. The clutch faces may be of the type shown in detail in Figures 8, 9, 5 and 10 and be formed as series of notches and teeth 35 and 36 respectively having inclined surfaces 37 and square shoulders 38 which interfit and cooperate for providing the driving connection, or, if preferred, the 10 clutch elements might be of the type shown in Figures 11 and 12, in which views, the elements 39 and 40 corresponding to the above described elements 29 and 30 are differently shaped, the teeth and notches, as 15 the case may be, being peripherally arranged instead of laterally as in the first described form. However, we do not desire to be limited to either of these clutch forms inasmuch as other varieties may be used to 20 equal advantage. The essential feature is that there should be a clutch mechanism within the drum for making it run idle when such is desired.

For controlling the rotation of the drum 25 when unreeling the cable, so as to prevent any possible back lash, we provide the flange 23 with a brake shoe 41 suitably mounted on its periphery and encircled by a contractile friction band 42 which has one end anchored at 43 and its other end connected with an angle lever 44 which is suitably pivoted as at 45 and which is operable to contract the band and apply frictional resistance to the rotation of the drum.

35 For anchoring the device and preventing it from movement when it is being used for pulling a stump, we provide a flexible member which is adapted to be engaged about a growing tree, rock or other stationary object and which has its ends 46 carrying clevises 47 detachably connected by pins 48 with the rear ends of the upright frames B.

In order that the device may be transported easily from place to place wherever 45 its use may be desired, we provide a wheel attachment which comprises a shaft 49 adapted to be engaged through openings 50 in the frame members B when it is intended to apply the wheel attachment. At the openings 50, the frames are formed with cam grooves 51 which open out to the sides as indicated at 52 and which receive and hold the transverse pins 53 which project beyond the shaft 49. By this arrangement it will be 55 seen that the shaft is inserted through the openings 50 in such a way that the pins 53 will engage within the cam grooves 51 and prevent longitudinal movement of the shaft 49. It will be apparent that only one opening 50 is provided with a cam groove as this is entirely sufficient. Detachably mounted on the ends of this shaft 49 are suitable ground engaging wheels 54 of sufficient diameter to support the base A above the ground.

65 When the device is merely being trans-

ported, the shaft 49 is in position and the wheels 54 are mounted on the shaft so as to support the entire device above the surface of the ground traveled over. The draw-bar I of the tractor is engaged with the forward end of the extension 9 by whatever pin is provided, which pin passes through the hole 28. The tractor may then pull the entire device bodily along the ground as clearly shown in Figure 2.

When use of the device is desired, the wheels 54 are removed and the shaft 49 preferably taken out of the frame so that the base of the device will rest upon the surface of the ground. The flexible member 46 is engaged about a free or other stationary object and the clevises 47 are connected with the rear ends of the frames B by means of the pins 48. The device is then firmly anchored so that it cannot move except in the arc of a circle concentric with the anchor. The tractor D is then backed up onto the base and the billet of wood used, as above described, to lift the tractor D, and permit it to drop onto the frames B so that the rear axle housing C will engage within the saddles 11. The caps 12 are applied and the tractor wheels E are removed, subsequently to which the sleeves 19 carrying the gears 20 are engaged upon the tractor spindles F and secured by means of the nuts G as above mentioned. The clutch lever 33 is thrown into such position as to disengage the clutch members 29 and 30, or 39 and 40, as the case may be, whereupon the drum will be idle on its shaft 14. The operator then takes hold of the cable 24 and unreels it from the drum until its free end can be looped about or otherwise secured to the stump to be pulled. When the tractor is subsequently operated and the clutch lever 33 moved to engage the clutch members 29 and 30, or 39 and 40 as the case may be, it is quite apparent that the drum 21 will be rotated and will operate to wind in the cable.

In case the device is not standing in an exact line between the anchor and the stump to be extracted, it is quite apparent that the first effect of the winding action of the drum will be to cause the entire device to slide upon the surface of the ground until it is in such alignment. The continued rotation of the drum causing winding in of the cable will naturally exert a pulling effect and cause extraction of the stump. Owing to the peculiar pan-shape of the bottom 6 of the base A it is quite apparent that the device will easily slide about as it may be necessary to do in order to secure the proper alignment. Naturally small rocks and other rough surfaces in the ground will not interfere with this sliding action.

The provision of the intermediate gears 16 is extremely important, the advantage

being that it is possible to have three speed forward which will enable the machine to move from one anchor to another with greater speed, and which will also increase the speed in pulling stumps. As a matter of fact it does not require the lowest speed or even the intermediate speed to pull small stumps; it being easily possible to extract them with the transmission of the tractor 10 in high gear. Furthermore, it is not necessary to dismount the tractor from the skid to move the device from place to place or from one anchor to another in pulling successive stumps. To move in this manner, 15 it is merely necessary to release the anchor rope and fasten the pulling rope to the next anchor and skid the machine to the same. This skidding from place to place can be done in high gear and without removing 20 the tractor from the skid, a circumstance which will mean a considerable saving in time.

When use of the device is no longer desired, the caps 12 are removed, the sleeves 25 19 carrying the gears 20 also removed, the tractor wheels E replaced and the billet of wood used in the reverse manner to that above described to permit the tractor to lift itself under its own power out of the 30 saddles 11 so that it may roll along and off from the base A. Subsequently to this the shaft 49 is replaced and the wheels 54 mounted thereon whereupon the device will be ready for transportation.

35 From the foregoing description and a study of the drawings it will be apparent that we have thus provided a comparatively simple and relatively inexpensive device for pulling stumps, the device being so arranged that use may be made of any ordinary or wellknown type of tractor for the application of power for driving the mechanism which winds in the cable for pulling the stumps. The device is bound to be 40 efficient in every way and a manifest convenience and time saver for those engaged in this work. Owing to the ruggedness of the construction it is apparent that the device should have maximum durability and 45 consequently long life.

50 While we have shown and described the preferred embodiment of the invention, it is of course to be understood that we reserve the right to make such changes in the form, construction and arrangement of parts as will not depart from the spirit of the invention or the scope of the subjoined claims.

Having thus described the invention, we 55 claim:

1. A device of the character described comprising a skid base, spaced upright frame members located on said base and formed with saddles adapted to support the 60 axle housings of a tractor, a windlass mech-

anism mounted upon the base, and a transmission mechanism for driving the windlass including gears adapted to be mounted upon the tractor spindles subsequent to the removal of the wheels therefrom.

2. In a device of the character described, 70 a skid base, spaced upright frame members mounted on said base and formed with saddles portions adapted to support the axle housings of a tractor, a winding drum carried by the frame members and a transmission mechanism for driving the drum including a gear carried by the drum, a counter shaft carrying a gear meshing with said first named gear, and a gear adapted 75 to be mounted upon a spindle of the tractor subsequent to the removal of the wheel therefrom and meshing with said second named gear.

3. In a device of the character described, 80 a skid base, spaced upright parallel frame members mounted on said base and provided with saddles adapted to support the axle housings of a tractor, a counter shaft journaled through the frames and carrying 85 gears, a windlass mechanism driven by said gears and including a releasable clutch element, and gears adapted to be mounted upon the tractor spindles subsequent to the removal of the wheels therefrom for driv- 90 ing the first named gears.

4. A device of the character described comprising a skid base, a cable guide at the forward end thereof, upright spaced frame members located on said base and 100 formed with saddles adapted to support the axle housings of a tractor, gears disposable upon the tractor spindles subsequent to the removal of the tractor wheels, a counter shaft journaled in said frames and carrying 105 gears meshing with said first named gears, a shaft journaled through said frames and carrying gears meshing with said second named gears, a drum rotatably mounted on said last named shaft, clutch means 110 for coupling said drum on its shaft, and means connected with one end of the skid base for anchoring the same, and a flexible member secured to and wrapped about the 115 drum and trained through said guide.

5. A device of the character described comprising a skid base, a cable guide at the forward end thereof, upright spaced frame members located on said base and formed with saddles adapted to support the axle 120 housings of a tractor, gears disposable upon the tractor spindles subsequent to the removal of the tractor wheels, a counter shaft journaled in said frames and carrying 125 gears meshing with said first named gears, a shaft journaled through said frames and carrying gears meshing with said second named gears, a drum rotatably mounted on said last named shaft, clutch means for coupling said drum onto its shaft, means 130

connected to one end of the skid base for anchoring the same, a flexible member secured to and wrapped about the drum and trained through said guide, the guide means including a frame, and pairs of vertical and horizontal rollers journaled therein and between which the cable passes.

6. A device of the character described comprising a skid base, a cable guide at the forward end thereof, upright spaced frame members located on said base and formed with saddles adapted to support the axle 35 housing of a tractor, gears disposable upon the tractor spindles subsequent to the removal of the tractor wheels, a counter shaft journaled in said frames and carrying gears meshing with said first named 40 gears, a shaft journaled through said frames and carrying gears meshing with said second named gears, a drum rotatably mounted on said last named shaft, clutch means for coupling said drum onto its shaft and 45 means connected with one end of the skid base for anchoring the same, a flexible member secured to and wrapped about the drum and trained through said guide, the clutch device being operable to permit the drum 50 to run freely upon its shaft with all the gears inactive, a brake device for regulating rotation of the drum, the brake device including a shoe carried by the drum at one end thereof, a contractile band encircling the shoe and having one end anchored, and a lever pivotally mounted and connected with the other end of the band.

In testimony whereof we affix our signatures.

ROBERT V. DAY.
ESTON RICKETSON.

7. A device of the character described
